UNITED STATES PATENT OFFICE.

LANSON B. JOYNER, OF ST. CLOUD, MINNESOTA.

INTERNAL-COMBUSTION ENGINE.

1,275,264.

Specification of Letters Patent. Patented Aug. 13, 1918.

Application filed November 6, 1916. Serial No. 129,858.

To all whom it may concern:

Be it known that I, LANSON B. JOYNER, a citizen of the United States, and a resident of St. Cloud, in the county of Stearns and State of Minnesota, have invented a certain new and useful Improvement in Internal-Combustion Engines, of which the following is a specification.

My present invention relates generally to an internal combustion engine, and more particularly to this character of engine of a type in which the piston is subjected to explosions upon both sides thereof, occurring in the opposite ends of its cylinder, my primary object being to provide certain improvements whereby this particular type of engine, ordinarily inefficient and impracticable, may be rendered effective and practicable, and utilized to efficiently perform the several functions, and in the several instances, for which the usual type of engine is employed.

These and certain other objects which will hereinafter more particularly appear, may be readily understood from the following description showing one manner in which my invention is carried out, and referring to the accompanying drawings illustrating the same and forming a part of this specification.

In these drawings:

Figure 1 is a side elevation illustrating my improvements;

Fig. 2 is an enlarged side view, partly broken away and in section, of a portion of the forward cylinder and the cross head;

Fig. 3 is a detail cross section taken substantially on line 3—3 of Fig. 2;

Fig. 4 is a rear end view;

Fig. 5 is a vertical longitudinal section through the forward cylinder;

Fig. 6 is a vertical cross section taken substantially on line 6—6 of Fig. 5;

Fig. 7 is a detail horizontal section taken substantially on line 7—7 of Fig. 6; and

Fig. 8 is a detail elevation showing the feed connection at the rear end of the piston rod.

Referring now to these figures, and particularly to Fig. 1, I have shown a pair of horizontally aligned axially disposed cylinders 10 and 11, each having upper intake valves 12 and lower exhaust valves 13 located adjacent the opposite ends thereof to pro-

vide for explosions within the opposite ends of each cylinder and upon relatively opposite sides of the intermediate piston 14 located within the cylinder as seen in Fig. 5. The piston rod 15 extends through the pistons 14 of the two cylinders 10 and 11, and is connected to a cross head 16 at its forward end, the latter being in turn connected by a pitman 17, to the crank 18 of the main shaft 19, which latter is connected through intermediate shafts 20 and 21, and gears 22, to a cam shaft 23 from which the intake and exhaust valves 12 and 13, as well as the spark plugs generally seen at 24, are controlled through cams 25 carried by the cam shaft 23, and rods 26, the latter having tappets 27 engaging the cams.

The cam shaft also preferably has a cam seen at 28 in Fig. 1 actuating the fuel pumps 29, pipes 30 from which lead to the carbureter 31 connected to the fuel pipe 32, the latter of which has branches leading into the several casings of the intake valves 12. This carbureter is preferably controlled from a governor 33 geared to one of the connecting gears 22 before described, for instance, through flexible connections extending through a pipe or other casing 34, in order to increase or decrease the fuel supply to the cylinders 10 and 11, in accordance with the speed of rotation of the driven shaft 19.

A magneto 35 may also be geared, as shown in Fig. 1, to one of the connecting gears 22 before described, to supply current to the several spark plugs 24 through connections as ordinarily used and not shown.

Internal combustion engines of the type above generally described have, heretofore, been impracticable and ineffective principally on account of the inability to properly cool the pistons and adjacent parts and pack the piston rod at the ends of the cylinder. In accordance with my improvements, however, the piston 14 of each cylinder, as particularly seen in Fig. 4, is provided with an inner solid portion 36 which screws upon an enlarged threaded portion 37 of the piston rod 15, the side walls 38 of the piston being spaced from its solid central portion to provide channels 39 at opposite sides of the latter and connected with one another by an annular series of transverse openings 40 whereby a complete circulation of a cool-

ing fluid may be had through the piston, the side walls 38 being provided with enlarged threaded openings coaxial with the rod 15, to receive the adjacent threaded end 5 of tubes 41 surrounding the rod 15 in spaced relation to the latter, so as to form an annular channel 42 through which the cooling fluid may flow to and from the pistons 14, the forward end of the forward tube 41, 10 as seen in Fig. 2, being threaded into a conformable bore in the cross head 16, from which a lateral port 43 opens into an outlet pipe in telescoping sections 44 and 45, the former of which is jointed at 46, leading to 15 a suitable tank 47.

The intake pipe 48 of a fluid pump 49 as seen in Fig. 1, which pump is driven, for instance through the sprocket and chain connection 50 as shown, from the main 20 shaft 19, extends from the tank 47 and the discharge pipe 51 of the pump leads rearwardly along one lower side of the cylinders 10 and 11 as seen by reference to Figs. 1, 4, and 6, with branches 52 leading 25 to the water jackets 53 of the cylinders 10 and 11, the rear end of pipe 51 being connected with an enlarged pipe 54 having a forward open end and disposed in axial alignment with the cylinders 10 and 11 at 30 the rear of the rear cylinder 10, to receive in telescoping relation therein the rear end of the rear tube 41 surrounding the rear portion of the piston rod 15.

Thus, a portion of the cooling fluid from 35 the pump 49, finds its way into the rear end of the sectional tube 41, and thus through the channel 42 thereof surrounding the piston rod, and successively through the pistons of the cylinders 10 and 11 to the 40 movable discharge pipe 44-45, another portion of such fluid from the pump finding its way into the water jacket 53 of the cylinders 10 and 11, from which it is directed through a discharge pipe 55, as seen in Fig. 45 1, back to the tank 47.

Thus the cooling fluid is pumped through the several pistons, as well as within the water jacket of the several cylinders, the fluid in the water jackets of the several cylinders 50 preferably finding its way into water jackets 56, seen in Fig. 5, and surrounding the casings 57 of the exhaust valves 13, which casings 57, as well as the casings 58 of the intake valve 12, are removably bolted 55 to their supports so that the intake and outlet valves may be bodily removed for convenient repair or substitution and to permit of ingress to the cylinders 10 and 11.

The casing 57 of each of the exhaust 60 valves is connected by a short connecting pipe 59, as seen in Fig. 7, to the exhaust pipe 60, common to both cylinders, and in order to effectively pack the piston rod with its sectional tube 41, I preferably provide each

of the cylinder heads 61 with an annular 65 rib 62, as best seen in Fig. 5, surrounding its opening, and providing for the effective engagement of the packing boxes 63 having internal packing rings 64 and internal annular grooves to receive the rib 62, the boxes 63 70 being to this end formed in two parts connected by connecting bolts 65 as plainly seen by reference to Fig. 4.

In the above manner I am enabled to promote sufficient circulation of cooling fluid 75 through the piston rod and piston to effectively cool these parts, which, together with the particular means of packing the piston rod, enables me to construct and operate for all of the purposes to which internal 80 combustion engines of this type are adapted, the engine as shown in a practical, efficient, and effective manner.

I claim:—

1. In an internal combustion engine of 85 the type described, a cylinder having combustion spaces adjacent opposite ends thereof, and fuel intake and exhaust connections communicating with said spaces, an intermediate piston within the cylinder having a 90 solid central portion and side walls spaced from the said central portion to form annular recesses adjacent the opposite sides of the piston, the said central portion having a series 95 of openings communicating between the said annular recesses, whereby to provide for the circulation of a cooling fluid through the piston, a piston rod on which the central solid portion of the piston is secured, tubes surrounding the piston rod in spaced relation 100 and connected to the side walls of the piston, said tubes forming annular channels around the piston rod, communicating with the spaces between the central solid portion of the side walls of the piston, and means for 105 effecting a circulation of cooling fluid through the said channels around the piston rod and the said circulating spaces of the piston.

2. In an internal combustion engine of the 110 type described, a cylinder having combustion spaces adjacent opposite ends thereof, and fuel intake and exhaust connections communicating with said spaces, an intermediate piston within the cylinder having 115 a solid central portion and side walls spaced from the said central portion to form annular recesses adjacent the opposite sides of the piston, the said central portion having a series of openings communicating between the said annular recesses, whereby to provide for the circulation of a cooling fluid 120 through the piston, a piston rod on which the central solid portion of the piston is secured, tubes surrounding the piston rod in spaced relation and connected to the side walls of the piston, said tubes forming annular channels around the piston rod com- 125

5
municating with the spaces between the central solid portion of the side walls of the piston, and means for effecting a circulation of cooling fluid through the said channels around the piston rod and the said circulating spaces of the piston, said side walls of the piston having threaded openings, and

said tubes around the piston being threaded for engagement with the said threaded apertures of the piston side walls.

LANSON B. JOYNER.
